UNITED STATES PATENT OFFICE.

DONALD M. MCLEAN, OF BOSTON, MASSACHUSETTS.

BAILED HOLLOW WARE.

SPECIFICATION forming part of Letters Patent No. 273,119, dated February 27, 1883.

Application filed August 2, 1882. (No model.)

To all whom it may concern:

Be it known that I, DONALD M. MCLEAN, of Boston, in the county of Suffolk and State of Massachusetts, have invented a new and useful Improvement in Hollow Ware, of which the following is a specification.

My said invention relates to any article of hollow ware on which is used the double bail described in Letters Patent No. 162,847, issued 10 to me May 4, 1875; and it consists in providing a means to control and guide the fluid contents of such articles while they are being poured out by combining with said double bail a nose place on the rim of said article between the pair of ends of said bail, on either 15 side of the article.

In the accompanying drawings, Figure 1 is a perspective view, and Fig. 2 a vertical section.

20 *a a* represent one pair of ends of said bail, and *a' a'* the other pair of ends; *c c* and *c' c'*, the ears to which the several ends of the bail are attached; *xx'*, the line of the central points

between the ends in each pair. *N* represents the said nose.

25 The full advantage of the double bail in emptying the article to which it is attached is only secured by tilting said article toward the point *x* or *x'*; but then the said ends and the ears to which they are attached obstruct the flow 30 of the fluid and scatter it into broken streams. This difficulty is removed by shaping the rim between the ends *a a* or *a' a'* into the nose *N*, by means of which the contents can be emptied with precision, as well as with safety and 35 convenience.

I claim as my invention in articles of hollow ware—

30 The nose *N*, in combination with the said double bail and ends *a a a' a'* thereof, in the 40 manner described.

DONALD M. MCLEAN.
